UNITED STATES PATENT OFFICE.

THOMAS PICTON BROWN, OF BELLEVILLE, CANADA.

DESIGN FOR A SHADE-ROLLER AXLE.

SPECIFICATION forming part of Design No. 27,719, dated October 12, 1897.

Application filed May 3, 1897. Serial No. 634,948. Term of patent 14 years.

To all whom it may concern:

Be it known that I, THOMAS PICTON BROWN, a British subject, residing at Belleville, in the county of Hastings and Province of Ontario, 5 Dominion of Canada, have invented and produced a new and original Design for Shade-Roller Axles, of which the following is a specification, reference being had to the accompanying drawings.

10 Figure 1 is a sectional view of my design, showing section of the hole B, passing entirely through the parts D, C, and A of my design. Fig. 2 is a side elevation of the same. Fig. 3 is a plan or end view, these three views being deemed necessary to fully illustrate my 15 design.

The leading feature of my design consists in a circular disk or flange D, having a raised boss C and a further circular perpendicular extension. When viewed in plan, as Fig. 3, 20 said extension A, Fig. 2, forms the bearing of axle and has a circular central hole B (shown in section in Fig. 1) passing entirely through both it and the boss C and disk or flange D.

Having described my design, what I claim 25 is—

The design for a shade-roller axle, as herein shown and described.

THOMAS PICTON BROWN.
